INVENTOR:

High H. Eby

UNITED STATES PATENT OFFICE

HUGH H. EBY, OF PHILADELPHIA, PENNSYLVANIA.

BINDING POST.

Application filed February 4, 1922. Serial No. 534,183.

The invention relates to binding posts as used in the electrical industry with electrical apparatus for securing an efficient electrical connection.

5 It has for its object a binding post which will receive and securely hold an electrical conductor equally well, whether large or small, which the binding post will accommodate without looping or bending the conductor and without injuring the conductor.

10 Large contact surfaces are provided and, with direct screw pressure, insure a positive contact.

15 A further object of this invention is to so design a binding post whose cap or clamping element will not come off the post or be bent. The post also presents a clean, smooth finish as no threads are exposed to collect dirt, grease, etc. The ease of operation eliminates any injury to the fingers.

20 The invention will be better understood when described in connection with the drawings:

25 Fig. 1 shows a partly sectioned elevation of the metallic portion of the top screw contact.

Fig. 2 shows a partly sectioned elevation of the metallic portion of the bottom contact.

30 Fig. 3 shows a bottom plan view of the metallic portion of the bottom contact.

Fig. 4 shows an elevation of the screw post.

35 Fig. 5 shows an assembly of Figs. 1, 2 and 4, the parts being partly sectioned.

Fig. 6 shows a partly sectioned elevation of Fig. 1 with insulation thereon.

Fig. 7 shows a bottom plan view of Fig. 6.

40 Fig. 8 shows a partly sectioned elevation of Fig. 2 with insulation thereon.

Fig. 9 shows a bottom plan view of Fig. 8.

Fig. 10 shows an elevation of the assembled post.

45 Referring again to the drawings; Fig. 4 shows the body portion 6 of the post proper which is threaded at the upper end at 9 to receive contact cap 7 (Fig. 1) which is correspondingly threaded internally over its inner portion at 10 with the same size of thread as on the post. The post is provided with a shoulder at 12 which is engaged by the flange 11 on cap 7 (Fig. 1) to limit the upward movement of the cap when said cap is raised by the screw action to

prevent removal of the cap. In this form 55 the post is inserted from the top of the cap.

The post 9 (Fig. 4) has a second shoulder 13 at an intermediate point in its length which affords a stop to determine the position of the lower contact member 8. The 60 lower contact member is internally threaded at 14 to fit over a thread 15 upon the lower end of the post and when secured to its desired position upon the post may be held there by upsetting the threads or by sweating it in position.

At a point 16 in the length of the post just above the upper surface of the lower member 8, an aperture is formed through which a conductor is passed which conductor is to be clamped between the two facing surfaces of the lower and upper contact elements.

70 The lower contact element is grooved at 17 and is flattened in its lower part at 18 75 for the purpose of better retaining a cover of insulating material 22 within which is placed a pin 19 intended to cooperate with the support to prevent turning of the binding post.

80 The upper contact member is knurled at 20 to receive and retain an insulating covering 21 which closes the upper end of the upper contact member against withdrawal of the binding post upwardly. The insulating material 21 of the upper contact member gives a larger and better holding surface for screwing the cap home and gives finish to the binding post as does the lower insulating material 22 about the lower contact member.

85 I show nuts 23 and washers 24 for holding the binding post in position and securing the electrical connection.

90 As thus presented the plain surface 25 is the only surface of the post 7 which is exposed when the cap is screwed up, so that the conductor is protected against engagement with binding post threads. The cap is protected against withdrawal.

95 I claim:

1. A binding post comprising a body portion threaded externally at both ends and two plain intermediate portions of different diameter forming a shoulder between the 105 plain portions, in combination with means for holding the binding post in position, engaging one threaded end and a cap engag-

ing the other threaded end, fitting over and close to the plain portion of smaller diameter, engaging the other thread and having an inwardly directed shoulder to engage the shoulder between the two plain portions.

2. A binding post stem threaded at both ends and having a plain portion adjacent the one thread and a shoulder between this plain portion and the other thread, in combination with a cap member engaging the second thread to move upon it during operation and having an inwardly directed shoulder to engage the shoulder first named.

3. In a binding post a stem having one end fitted for attachment of the post, the

other end enlarged and threaded, an intermediate plain portion having an opening and a shoulder adjacent this plain portion and spaced from the threaded end, in combination with a cap member forming in normal operation threaded engagement with the thread of the stem and having an in-turned flange fitting close to the plain portion and engaging the shoulder at its outer limit.

Signed at Philadelphia, in the county of Philadelphia and State of Pennsylvania this 18th day of July, 1921.

HUGH H. EBY.
